Marshall B. Stafford

UNITED STATES PATENT OFFICE.

MARSHALL B. STAFFORD, OF NEW YORK, N. Y.

MEANS OF VENTILATION.

SPECIFICATION forming part of Letters Patent No. 297,189, dated April 22, 1884.

Application filed May 3, 1883. (No model.)

To all whom it may concern:

Be it known that I, MARSHALL B. STAFFORD, a citizen of the United States, residing at New York, in the county of New York and State of New York, have invented certain new and useful Improvements in the Means of Ventilation; and I do hereby declare the following to be a full, clear, and exact description of the invention, such as will enable others skilled in the art to which it appertains to make and use the same.

The invention relates to an improved means for ventilating buildings and for equalizing and regulating the temperature thereof. It is based upon the theory that foul air is heavier than pure air, and consequently falls to the floor, and that from its nature it can only be removed by positive means, it having no tendency to pass off in a current unless impelled so to do by means other than the mere admission of fresh air. According to this theory, the pure air will be in the upper portion of the apartment, where it will not be available to the occupants unless the foul air is removed and it is brought down to fill the vacuum thereby created. According to my invention this result is attained, and fresh air is admitted above and in proportion to the volume of air thus lowered. By this method of ventilation the air is not only kept pure, but the temperature of the apartment is equalized and regulated.

The purposes of my invention are accomplished by means of a series of pipes passing through the building and connecting with the lower part of each apartment thereof, a suction-blower being provided in the cellar to extract the foul air, and by means of fresh-air flues extending into the building from the roof, and having inlets at the upper portion of the separate apartments, said inlets being supplied with valves which are actuated by the extraction of the foul air to admit an adequate supply of fresh air.

The invention is especially valuable in the winter season, since by it the heated air is gradually lowered, and is not removed until it has become impure, and the fresh air is tempered before it can be inhaled by the occupants of the building.

The exact nature and operation of the invention will be readily understood from the description hereinafter presented, reference being had to Figure 1 of the drawings, which represents a sectional view illustrating my system of ventilation in connection with a building. Fig. 2 is an enlarged view showing the inlet-valve.

A denotes the flues for the fresh air, which have openings at the upper part of the building, and are connected with the rooms B at their upper portions by the inlets C.

In the inlets C are provided the flap-valves a, which are hung loosely, so as to be capable of being easily swung on their supports by the movement of the air, as hereinbefore described.

In the lower part of the building is placed a suction-blower, D, connecting with the vertical pipe E, from the upper end of which extend the branch pipes F G, passing to the upper floor of the building.

From the vertical pipes F G project branch pipes H, which pass beneath the floors and have openings I, provided with registers J. The branch pipes H are connected by the usual elbows, &c., with the vertical pipes F G, so that one or more pipes extending through the building will be sufficient to receive the foul air drawn from all of the rooms.

By the employment of the registers J, any one or more of the rooms may be disconnected from the ventilating apparatus and the full force of the suction-blower D utilized in purifying the atmosphere of the remaining rooms.

It will appear obvious that when the blower D is set in operation the foul air will be drawn from the rooms through the pipes F G and branch pipes H, and that fresh air will be admitted through the inlets B to supply the place of the extracted air. If the quantity of air drawn from the room is large, the vacuum thus created will operate to open the valve a a proper distance to admit a corresponding supply of air, and when the air extracted by the suction-blower is small the opening of the valve a will be correspondingly slight and a proportionate quantity of fresh air will be admitted. It will be seen, therefore, that I am enabled in my system of ventilation to provide a regular and constant supply of fresh air.

by means which are actuated according to the amount of foul air extracted.

It will appear plain that by drawing the foul air from the lower part of the room the warm 5 pure air at the upper part will gradually lower, and that the temperature of the room will thus be rendered uniform throughout, and the best results from the heating medium will be realized.

10 What I claim as my invention, and desire to secure by Letters Patent, is—

An improved means for ventilating buildings and equalizing the temperature therein, which consists of the fresh-air flue A, leading 15 from the roof and connected with the upper

part of the apartments by flues C, having automatically operating valves *a a*, suction-blower D, a foul-air pipe which extends upward through the building, and whose lower end connects with the suction-blower, and a 20 series of branch pipes, H, which lead from the foul-air pipe to the lower part of the separate apartments, and are provided at their mouth with registers J, substantially as set forth.

In testimony whereof I affix my signature in 25 presence of two witnesses.

MARSHALL B. STAFFORD.
